(57) CLAIM

(21) Appl. No.: **29/106,283**

The ornamental design for an egg knot twist roll maker, as shown.

(22) Filed: **Jun. 11, 1999**

DESCRIPTION

(51) LOC (7) Cl. **31-00**

FIG. 1 is a front perspective view of the egg knot roll maker according to the invention;

(52) U.S. Cl. **D7/387**

FIG. 2 is a side view of the egg knot roll maker according to the invention;

(58) Field of Search D7/672, 682, 376,
D7/381, 384, 387, 213; 99/509; 366/342,
349; 241/291, 301; D15/122, 123, 127,
135, 136, 138, 139

FIG. 3 is an opposite side view of the egg knot roll maker according to the invention;

(56) References Cited

FIG. 4 is a back perspective view of the egg knot roll maker according to the invention;

U.S. PATENT DOCUMENTS

FIG. 5 is a front view of the egg knot roll maker; and,

D. 56,119 * 8/1920 Crisenberry D7/682

FIG. 6 is a back view of the egg knot roll maker.
